No. 809,857.

PATENTED JAN. 9, 1906.

A. STENWALL.
SLIDE GATE VALVE.
APPLICATION FILED DEC. 24, 1904.

UNITED STATES PATENT OFFICE.

ALFRED STENWALL, OF KEWANEE, ILLINOIS.

SLIDE-GATE VALVE.

No. 809,857.

Specification of Letters Patent.

Patented Jan. 9, 1906.

Application filed December 24, 1904. Serial No. 238,256.

To all whom it may concern:

Be it known that I, ALFRED STENWALL, a citizen of the United States, residing at Kewanee, in the county of Henry and State of Illinois, have invented certain new and useful Improvements in Slide-Gate Valves; and I do hereby declare the following to be a full, clear, and exact description of the invention, such as will enable others skilled in the art to which it appertains to make and use the same.

Slide-gate valves as almost universally constructed are provided with screw-stems to raise and lower the gates, and the speed or motion of the gates by such means is necessarily, of course, limited according to the pitch of threads used, requiring several full revolutions of the valve-stem fully to open or to close the gates.

The object of my invention, therefore, is largely to increase the degree of rapidity of motion of the gates to the end that a fraction of a turn only of the valve-stem shall be amply sufficient fully to open or to close the gates. The desirability and value of my construction are apparent, as almost instant communication through the valve or stoppage of the flow therethrough may be effected, as well as a great saving of time.

A further object of my invention is to provide an improved form of slide-gate valve which will operate in an exceedingly rapid and thoroughly efficient manner and the parts of which shall not be liable to get out of order.

With these objects in view, as well as others which will appear as the description proceeds, my invention consists in the construction, combination, and arrangement of parts, as fully hereinafter described and claimed.

In the drawings, Figure 1 is a central vertical section of my valve. Fig. 2 is a detail view of the valve-stem and of one of the valve-gates carried thereby. Fig. 3 is a perspective detail view of one of the gates. Fig. 4 is a central vertical section of my invention embodied in an angle gate-valve, and showing a different form of stuffing-gland, and Fig. 5 is a detail top plan of the stuffing-gland shown in Fig. 4.

Referring to the drawings, A designates the valve-body, provided with internally-threaded ends a , preferably of shape to conform to standard-sized piping and with an extension a' , having an annular flange a^2 , exteriorly

threaded, on which is secured a hood a^3 , provided with a similar flange a^4 , interiorly threaded. The extension a' provides an interior chamber a^{22} . The barrel portion a^5 of the hood may be interiorly threaded a portion of its length for the reception of a stuffing-gland a^6 , similarly threaded, and in addition packing a^7 may be utilized in the barrel portion, which packing is tightly pressed by the gland a^6 , preventing leakage of fluid around the valve-stem a^8 . Interiorly of the valve-body A may be two annular flanges forming valve-seats a^9 . The valve-stem a^8 is formed threadless and preferably carries the usual handle a^{10} , and the stuffing arrangement a^6 and a^7 , already described, serves as a frictional means sufficient to retain the valve-stem in any adjusted position and to overcome the force of gravity tending to make the valve-stem drop after being raised. Integral with the lower end of the valve-stem is a beveled gear-pinion a^{11} , and carried by the stem a^8 is a grate-carrying member comprising a substantially horizontal plate a^{12} , swiveled on the stem a^8 . Directly above the pinion a^{11} is an armed or forked yoke a^{13} , depending from this plate a^{12} , the yoke being provided with a hole a^{14} through its lower portion.

The valve-gates are each provided on one side with a smooth face a^{16} to engage the smooth inner face of the valve-seats a^9 , with beveled spur-teeth a^{17} around the edge of its other face a^{18} to mesh with the pinion a^{11} and with a projection a^{19} also on the face a^{18} , the projection being formed on its end with a cam a^{20} . The projections a^{19} exactly fit into but have free rotary movement in the opening a^{14} of the yoke a^{13} , the yoke thus serving to keep the gates spaced apart a proper distance.

Desirably one row each of rack-teeth a^{21} is formed in two of the walls of the internal chamber a^{22} of extension a' (the two rows being preferably disposed diagonally opposite each other) and are engaged by the beveled spur-teeth a^{17} of the gates.

The operation is as follows: The sliding gates being at the extreme downward limit of their range of movement, rotary movement of the valve-stem by its handle in one direction imparts similar movement to its beveled gear-pinion a^{11} , the teeth of which are in mesh with the teeth a^{17} of the gates, thus imparting rolling movement to the gates, the teeth a^{17}

of which are also in mesh with the rack-teeth a^{21} in the walls of chamber a^{22} , the gates thereby rolling up on the rack-teeth a^{21} . Only a part of a turn of the valve-stem is fully sufficient entirely to open the gates, frictional engagement of the valve-stem with the tightly-wedged packing a^7 holding the valve-stem in any adjusted position. Only part revolution of the stem in the reverse direction will quickly close the gates, and when they are at the extreme downward limit of their range of movement the cams a^{20} on the inner faces of the gates abut, thus spreading the gates outward slightly or away from each other, causing the outer smooth faces a^{16} of the gates firmly to engage the annular flanges or valve-seats a^9 , insuring that communication through the valve-body A shall be entirely closed and that there shall be no possible leakage around the gates.

Fig. 4 shows my invention applied to an angle gate-valve, in which B represents the inlet portion of the valve-body and B' the exit thereof at an angle to the inlet. All parts of my invention are the same as shown in the previous figures of the drawings.

In large valves it may be advisable to utilize means in addition to the frictional contact of the packing with the valve-stem, as already described, for holding the valve-stem in any desired raised or partly-lowered position. In Figs. 4 and 5 I have shown what I term a "locking packing-gland" C, which, as its name implies, subserves two useful and important functions—namely, to lock the valve-stem in any desired position of vertical adjustment and to pack the stuffing a^7 in the barrel portion a^5 of the device. For these purposes I construct the locking packing-gland with a split body portion c , externally threaded at its lower end to engage with the internal threads of the barrel portion a^5 , thus tightly to pack the stuffing a^7 and prevent any leakage around the valve-stem, and with a correspondingly split head c' . Through the head c' passes a tightening-screw c^2 , in the head c^3 of which is swiveled a turning-handle c^4 , all as shown clearly in Figs. 4 and 5. The operation of this split locking packing-gland is obvious and provides an efficient means of positively locking the stem in any desired raised or partially-lowered position and at the same time to pack the stuffing around the valve-stem in the barrel portion, thus to prevent any leakage.

Having thus fully described my invention, what I claim as new, and desire to secure by Letter Patent, is—

1. In a slide-gate valve, the combination with the valve-body provided with a passage therethrough, of a chamber disposed at an angle to the passage and communicating therewith, rack-teeth disposed on the walls of the

chamber, a valve-stem carrying an integral gear-pinion and a swiveled yoke toward its lower end, the yoke being formed with an opening therethrough, gates provided with projections on their inner faces adapted to enter the opening of the yoke, and provided along their edges with spur-teeth in mesh with the teeth of the gear-pinion on the valve-stem and with the rack-teeth disposed on the walls of the chamber, and cams on the ends of the projections of the gates, adapted to engage each other when the gates approach their seats, thus to spread the gates apart and cause them firmly to engage their seats.

2. In a slide-gate valve, the combination with the valve-body provided with a passage therethrough, of a chamber disposed at an angle to the passage and communicating therewith; rack-teeth disposed on the walls of the chamber; a valve-stem carrying a gear-pinion; a gate-carrying member, comprising a substantially horizontal plate or bar swiveled on the valve-stem at its lower end, and a yoke depending from the plate and provided with an opening therethrough; gates provided with projections on their inner faces adapted to enter the opening of the yoke, and provided along their edges with spur-teeth in mesh with the teeth of the gear-pinion on the valve-stem and with the rack-teeth disposed on the walls of the chamber.

3. In a slide-gate valve, the combination with the valve-body provided with a passage therethrough, of a chamber disposed at an angle to the passage and communicating therewith; rack-teeth disposed on the walls of the chamber; a valve-stem carrying a gear-pinion; a gate-carrying member, comprising a substantially horizontal plate or bar swiveled on the valve-stem at its lower end, and an armed or forked yoke depending by its forks from the plate, said yoke being provided with an opening through its lower portion; gates provided with projections on their inner faces adapted to enter the opening of the yoke, and provided along their edges with spur-teeth in mesh with the teeth of the gear-pinion on the valve-stem and with the rack-teeth disposed on the walls of the chamber.

4. In a slide-gate valve, the combination with the valve-body provided with a passage therethrough, of a chamber disposed at an angle to the passage and communicating therewith; a hood secured over said chamber and formed with a barrel portion having a central bore; a valve-stem passing through the bore of the hood, depending into the chamber, and carrying a gear-pinion toward its lower end; means exerting pressure on the valve-stem whereby the same is frictionally held in any desired position of vertical adjustment; a gate-carrying member, comprising a substantially horizontal plate or bar swiveled on the valve-

stem at its lower end, and an armed or forked yoke depending by its forks from the plate, said yoke being provided with an opening through its lower portion; gates provided 5 with projections on their inner faces adapted to enter the opening of the yoke, and provided along their edges with spur-teeth in mesh with the teeth of the gear-pinion on the valve-stem

and with the rack-teeth disposed on the walls of the chamber.

In testimony whereof I affix my signature in the presence of two subscribing witnesses.

ALFRED STENWALL.
